UNITED STATES PATENT OFFICE.

LE ROY W. STANTON, OF CLEVELAND, OHIO, ASSIGNOR OF ONE-HALF TO FRANCIS W. DUNBAR, OF CHICAGO, ILLINOIS.

TELEPHONE SYSTEM.

1,156,253.

Specification of Letters Patent. Patented Oct. 12, 1915.

Application filed November 8, 1912. Serial No. 730,283.

To all whom it may concern:

Be it known that I, LE ROY W. STANTON, a citizen of the United States, residing at Cleveland, in the county of Cuyahoga and State of Ohio, have invented certain new and useful Improvements in Telephone Systems, of which the following is a specification.

The present invention relates generally to 10 telephone systems and more particularly to telephone systems in which an operator receives an order and performs some act in the establishment of connections between telephone lines, whether those lines be the lines 15 of subscribers or lines available to, or associated with, operators, as in so-called "trunking" systems.

The principal objects of this invention are, first, to increase the efficiency of such 20 systems by reducing the time required to put through connections and, second, to increase the efficiency of such systems by reducing the errors incidental to present practice. In brief, these objects are attained by 25 providing means for indicating to a calling party when the operator is free to receive and carry out such party's order without requiring the operator to speak to such party. In other words, a party who initiates a call 30 waits until he receives a definite, preferably automatic, indication of the operator's attention before giving his order; the arrangement of the circuits and apparatus being such that this indication is not perfected until the circuits between the calling party and 35 the operator have been completed and the operator is at liberty to receive the order. This feature of my invention is capable of 40 general application to systems employing an operator, or operators.

By way of illustration, I have disclosed my invention in connection with a semi-automatic system such as illustrated in Figure 1 of British Patent No. 11,290 of 1905. The 45 invention might equally well have been disclosed in connection with other well known systems.

Other features of the invention reside in 50 novel means for guarding the operator's set against connection while in use and for testing a plurality of operators' sets and connecting with the first set found to be idle.

Still other features and advantages of my 55 invention will be apparent from the following detailed description taken in connection with the accompanying drawing, and the

scope of the invention will be particularly pointed out in the appended claims.

The drawing is a diagram of a semi-automatic system embodying the invention and employing both manual and automatic switches; the same, as before indicated, illustrating the application of my invention to the particular system illustrated in Fig. 1 of the aforesaid British patent.

Throughout this drawing, like characters refer to like parts.

In the system illustrated, each subscriber's line is provided with an automatic switch which has access to a plurality of link-circuits which terminate in plugs adapted for connection to other telephone lines.

The diagram illustrates one subscriber's substation and telephone line, one switch associated with said line, the multiple bank contacts of a second switch, one link-circuit in full, a second link-circuit with parts omitted, and a plurality of lines to which the link-circuits may be connected by means of manual switches, consisting in the present 75 instance of plugs and jacks. It is, of course, to be understood that in practice, a plurality of subscribers' lines will be employed in connection with a plurality of link-circuits and that the latter will be arranged for connection with any one of a number of other telephone lines, which may be either subscribers' lines such as that illustrated, party lines such as shown in the aforesaid British 80 patent, trunk lines, or any other desired 85 circuits.

Referring to the drawing in detail, A designates a substation connected by a telephone line L with the exchange where switch M, individual to the line, is arranged 90 to extend its circuit to link-circuits, such as N, which terminate in plugs P arranged for connection with the jacks of other telephone lines L' and L².

At the substation, 10 designates a transmitter which is included with an impedance coil 11 in a normally open bridge of the limbs 12 and 13 of line L. A call bell 14 and a condenser 15 are in a normally closed bridge of these same line limbs. When the receiver 16 is removed from the switch-hook 17, the bridge through the bell 14 is broken and that through the transmitter 10 is closed. The closing of the latter brings the condenser 15 and receiver 16 into shunt with the impedance coil 11. This substation circuit is well known and is merely illustrative.

Other substation circuits might equally well be employed.

- The line circuit includes the line relay 18, cut-off relay 19, control relay 20, and their associated contacts and connections. Line limb 12 is normally connected to ground through back contact 21 of relay 19, and line limb 13 is similarly connected by back contact 22 with winding 23 of line relay 18 to the live pole of battery B. A second winding 24 of relay 18 is adapted to be included in circuit through front contact 25 with an interrupter 26, and any fitting source of current such as battery 26'. It is by this circuit that an inductive disturbance is placed upon the calling line as part of the signaling arrangement for indicating to the calling party when the operator is ready to receive his order. Conductors 27 and 28 connect with conductors 29 and 30 to extend the line limbs 12 and 13 to the switch M, conductors 27 and 29 continuing line limb 12 through back contact 31 of relay 20, and conductors 28 and 30 continuing line limb 13 through back contact 32 of the same relay. Contacts 33 and 34 of relay 20 and contacts 35 and 36 of line relay 18 coöperate in the control of the switch M.
- The switch M, as diagrammatically shown, includes the line wipers 37 and 38 and a private or test wiper 39. These wipers coöperate, respectively, with bank contacts 40, 41 and 42. In operation, these wipers move from the position illustrated, over these contacts to the left in response to energizations of the motor magnet 43 which operates its armature 44 to cause its spring pressed driving pawl 44' to engage the ratchet teeth 45 to give the switch successive steps. The armature 44 is returned to normal by a spring 44'', and the pawl 44' being yieldingly pivoted, slips by the teeth on each return stroke. A lazy arm 46, actuated by an insulating projection 47 carried by the armature 44, automatically makes and breaks the circuit of the motor magnet 43. A retaining pawl 48 engages the teeth 45 to retain the switch in the positions to which it is advanced by the magnet 43. A spring 49 acts upon the retaining pawl 48 to hold it in engaging positions, but allows it to be removed therefrom by the spring catch 50 having a hooked end adapted to engage a hooked projection 51 upon the said retaining pawl to lift it out of engagement in response to the return stroke of armature 52 of the release magnet 53. A spring 54 normally tends to hold the armature 52 in its retracted position. When the retaining pawl 48 is withdrawn, a spring 55, coiled about the shank of the movable element of the switch and acting against an abutment 56, restores the switch to its normal position. Upon such restoration, the insulating projection 57 upon the lateral arm 58 moves

the spring catch 50 out of engagement with the retaining pawl 48 and allows it to return to operative relation with the teeth 45. Normally-open contacts 59 and 60 are arranged in the path of movement of the insulating projection 61 upon the movable element of the switch so as to be moved into engagement by such projection when the switch has overrun its operative contacts. This, as will appear hereinafter more fully, 75 brings about a release of the switch. A protective resistance 61 is included between the live pole of the battery B and the contact 60.

As before stated, a single switch M only is fully diagrammatically illustrated. The contacts 62, 63, 64 are the contacts of a second, or other, switch corresponding to the contacts 40, 41, and 42. Such second, or other, switch, it will be understood, is to be associated with some other telephone line 80 and is to be provided with circuits such as those shown in connection with switch M. These contacts 62, 63 and 64 are multiply connected with contacts 40, 41, and 42 respectively and illustrate how contacts of a 85 third and fourth, or any desired number of switches are to be associated to provide a plurality of link-circuits available to any one of a plurality of telephone lines.

The link-circuits, to which the switch M 90 and all other similar switches of the same group have access, comprise, respectively, a tip strand 65, a sleeve strand 66 and an additional control strand 67. In the diagram, a plurality of such sets of strands are indicated. One is shown in full and is that one encountered upon the first step from normal of the switch shown in full. Another is shown in part and is that engaged upon the fifth step of the same switch. Others are indicated by the multiple strand connections to contacts 40, 62 in the case of the tip strand, contacts 41, 63 in the case of the sleeve strand, and contacts 42, 64 in the case of the control strand. These latter correspond to each of the other steps of the switch shown in full. As here shown, the link-circuits of the first four encountered contacts have one operator's transmitter 68 and receiver 69 and one control relay 70 common to them, while the second four have a second operator's receiver and transmitter and a second relay 70 common to them.

The illustration is, of course, not limited to two operators' positions, nor to a definite number of cords for any position. Each link-circuit N includes a sleeve relay 71 and a tip relay 72 associated with the switch end of the link-circuit and a sleeve relay 73 and tip relay 74 associated with the opposite, or connecting, end of the link-circuit. These relays possess a plurality of functions. They control the supervisory lamps 75 and 76. This control is exercised through the contacts 77 and 78 of relays 71 and 72 for 120 125 130

lamp 75 and through the contacts 79 and 80 of relays 73 and 74 for lamp 76. Pilot relays 81 and 82, common to a group of link-circuits, control, by contacts 85 and 86 respectively, corresponding pilot lamps 83 and 84. The control relay 70 is common to a group of link-circuits and is controlled by means of a plurality of series of relay contacts, one series of such contacts being provided in each link-circuit of the group. Its circuit can only be closed through the simultaneous closure of a series of contacts including contact 87 of a relay 73, contact 88 of a relay 71, and contact 89 of a relay 72. Each link-circuit controls a call lamp 90. Its circuit extends through a front contact 91 of relay 72, a back contact 92 of relay 73 and a front contact 93 of relay 71. The switch release circuit of each link-circuit is closed from battery B through common relay 82, contact 93 of relay 71, contact 92 of relay 73 back contact 91 of relay 72, conductor 67, back contact 36 of relay 18 and release magnet 53 to ground. The operator's receiver, 69, is included in circuit with the secondary winding of the induction coil 94 and with the condenser 95. The two common sides of this circuit extend through back contacts, 96 and 97 of each relay 73, front contacts 98 and 99 of each relay 71 and front contacts 100 and 101 of each relay 72, comprehended in each of the link-circuits common to an operator's position. Condensers 102 and 103, provided for each link-circuit terminal are included in the talking strands 65 and 66 respectively. The primary winding of the induction coil 94 may, as shown, be connected in series with the operator's transmitter 68, and branches thereof may extend to ground through one winding of the impedance coil 104, and through condenser 105, in parallel therewith; or other certain well known circuit arrangements may be employed. Test relay 107 is common to the same link-circuits as the operator's set with which it is associated. As illustrated, it is controlled through the back contacts of the sleeve relays 73 of the associated link-circuits, while the relays 74 are controlled through front contacts 108. As illustrated, the armature 106 of the test relay 107 is attracted and causes a momentary disturbance, or click, in the operator's circuit, when a busy line is tested. Each control relay 70, when energized, connects the conductors 67 of all the link-circuits to which the said relay 70 is common, directly to ground through a protective resistance 109. This connection is brought about by armature contact 110 and individual contacts 111, 112, 113, 114 etc., one such contact being provided for each link-circuit of a group. In other words, one such contact will be provided for each link-circuit common to the relay 70. Ring-

ing key 115—116, when operated, breaks the strands 65 and 66 and brings the ringing generator 117 and the impedance coil 118 into circuit. Similarly, ringing key 119—120 brings ringing generator 121 into circuit. 70

The telephone lines L' and L'', as before indicated, may be subscribers' lines similar to the line L upon which there is a single substation, or a subscriber's line having a plurality of substations, such as shown in the aforesaid British patent. Or again, the telephone lines L' and L'' may be trunk lines extending to a distant exchange, or exchanges, or to another part, or other parts, 80 of the same exchange. Or they may be other circuits with which the link-circuits are capable of use. The lines L' and L'' are provided with multiple jacks 122 and 123 available to the different groups of link-circuits N. These jacks are provided for the reception of the plugs P of such circuits. Similar multiple jacks 124 are provided for the subscriber's line L, their tip and sleeve contacts being connected, respectively, to 90 extension conductors 27 and 28.

In the operation of the system, if it be assumed that a party at substation A desires to converse with a party having a station on line L', or upon a line reached by way of line L', then, upon removing his receiver 16 from its switch-hook 17, a circuit will be completed through the line relay 18, through winding 23 of said relay, the back contacts 21 and 22, the line limbs 12 and 13, and the bridge through transmitter 10 and induction coil 11. The resulting energization of line relay 18 immediately closes the circuit of interrupter 26 and, by reason of the transformer action of the windings 23 and 24 of relay 18, current is induced upon the line L such as to produce a noise or "buzz" in the receiver 16. In this form of the invention, this "buzzing" noise continues until the selected operator is ready to receive the order of the calling party. Being instructed as to this operation of the system, the calling party awaits the discontinuance of this noise before entering his order. The energization of line relay 18 also closes a circuit 110 for control relay 20 which may be traced from battery, through the winding of said relay, front contact 36, wiper 39, to ground at 125. The resulting energization of relay 20 opens contacts 31 and 32, thereby disconnecting wipers 37 and 38, during their advance movement so as to prevent interference with conversations over multiply connected circuits. The energization of relays 18 and 20 also closes a circuit for motor magnet 43 which may be traced from the live pole of the battery, through the winding of said magnet 43, lazy arm contact 46 and front contacts 35 and 33 to ground at 126. Upon the first energization of magnet 43, 130

stepping pawl 44 advances the wipers 37, 38 and 39 one step. If the contact 42 corresponding to this first step be grounded either by reason of a connection to ground 5 through contact 110—111 of relay 70, or by reason of a previous connection extending to ground through another multiple contact 64 via a wiper 39 of some other switch and its associated back contact 36, and with the 10 winding of release relay 53 of that switch, the switch continues to advance, and advances as long as such grounded condition is encountered, the circuit of relay 20 being maintained and the motor magnet 43 15 advancing the switch step by step. When, however, a link-circuit is found which is not guarded by such a ground, of either nature, then strand 67 is open and there being no connection for relay 20 extending to 20 ground through the wiper 39 is deenergized and the switch stops with its wipers in engagement with the strands 65 and 66 of the selected link-circuit. The closure of contacts 31 and 32 unites the extension conductors 27—28 and 29—30. As soon as this 25 takes place, a circuit is completed through sleeve supervisory relay 71 and cut-off relay 19. This circuit may be traced from battery, through the winding of relay 71, strand 66, 30 contact 41, wiper 38, conductor 30, back contact 32, conductor 28 and winding of cut-off relay 19 to ground. As a result, relay 19 35 interrupts the circuit through the line relay 18 and thereby removes the special signal from the calling party's circuit and therefore indicates to him that the apparatus is in condition for him to give his order to the operator. This occurs simultaneously with the completion of the operator's circuit, including the transmitter 68 and the receiver 69. The operator is thus free to receive the order. The closing of the front contacts 21 and 22 of relay 19 extends the circuit of the line limbs 12 and 13 through to the link-circuit strands 65 and 66. The closing of 40 front contact 22 also provides a path for the flow of current in shunt with the cut-off relay 19, out over line limb 13, through the substation and back through line limb 12, 45 through the extension conductors 27 and 29 to tip strand 65 of the link-circuit, and thence to ground through tip supervisory relay 72. The closing of this circuit energizes relay 72 which results in the lighting 50 of pilot lamp 84 and in lighting of the call lamp 90 which is individual to the particular link-circuit selected.

It may be pointed out here that the adjustments of relays 18 and 71 and 53 are 55 such as to render said relays sluggish so that tip relay 72 will have time to be actuated to open its back contact 91 before the release magnet 53 can be operated, in case the release circuit should be momentarily closed, 60 the circuit, as before traced, extending from the live pole of battery B, through relay 82, front contact 93 of relay 71, back contact 92 of relay 73, back contact 91 of relay 72, conductor 67, switch contact 42, wiper 39, back contact 36 of relay 18, and the winding of release magnet 53 to ground.

The lighting of lamps 84 and 90 is brought about upon the energization of relays 71 and 72. A circuit then extends from the live pole of battery B, through the winding of relay 82, front contact 93 of relay 71, back contact 92 of relay 73, front contact 91 of relay 72, and the lamp 90 to ground. This circuit lights the lamp 90 and energizes relay 82 to close its front contact 86 to complete a circuit from battery, through pilot lamp 84 to ground. The lighting of the lamp 90 indicates to the operator which link-circuit N the call is coming in on and indicates to her which plug P 85 to pick up for readiness in extending the call. The energization of relays 71 and 72 also closes a circuit for control relay 70 of the group of link circuits which includes the one selected. This circuit extends from the live pole of Battery B, through the winding of relay 70, back contact 87 of relay 73, front contact 88 of relay 71, and front contact 89 of relay 72, to ground. The energization of relay 70, as a result of the closing of this circuit, closes its contact 110 upon contacts 111, 112, 113, 114, etc., and thereby places a ground connection directly upon the conductor 67 of the several link-circuits of the group. As before pointed out, the switches will not stop in connection with link-circuits upon which this ground connection exists. The energization of relays 71 and 72 also connects the operator's set, including transmitter 68 and receiver 69, into circuit with the strands 65 and 66, the receiver being placed directly in bridge of these strands. This bridge circuit may be traced from strand 65, through front contact 101 of relay 72, front contacts 98 of relay 71, back contact 97 of relay 73, the secondary winding of induction coil 94, receiver 69, condenser 95, back contact 96 of relay 73, front contact 99 of relay 71, front contact 100 of relay 72, to strand 66. The primary portion of this circuit extends from the live pole of battery B, through the primary winding induction coil 94, transmitter 68, and thence through impedance coil 104, and condenser 105 in parallel therewith, to ground. Because the energization of relays 71 and 72 and the deenergization of relay 73 are required to connect the operator's set into circuit and because this condition is required to cause the operation of relay 70 to momentarily guard any of the link-circuits to which the operator's set is common from selection, it will be seen that the switches M will not stop in engagement with link-circuit N unless the operator's set com-

mon to such link-circuits is free and the operator ready to receive an order from the calling party. When such connecting condition does occur, the characteristic noise or distinctive signal in the calling party's receiver is removed as a result of the de-energization of line relay 18, as before explained. As soon as the calling party observes the discontinuance of this characteristic sound, he will know that he is to give his order to the operator. The conversational circuit between the calling party and the operator includes the heavy line conductors to the left of condensers 102 and 103, the calling party's transmitter and receiver, and the operator's transmitter and receiver; the receiver of the latter being in bridge of the strands 65 and 66 as previously traced and her transmitter being in inductive relation thereto. Upon receiving the order, the operator will insert the plug P, associated with that particular link-circuit, into a multiple jack 122 of the particular line, such as L', through which the circuit is to be extended in response to the order, provided such line, upon test, is found idle. In making the busy test, the operator touches the tip of her plug P against the sleeve contact of jack 122 of the line with which connection is desired. In case the line is in use, there will be an electrical potential upon such sleeve contact which will produce a current flow from the tip of the plug, through the sleeve strand 65, back contact 108 of relay 73, the winding of relay 107, to ground. This flow of current will energize relay 107 to close its contact 106 and produce a momentary short circuit of the branches through coil 104 and condenser 105. The result will be a "click" in the receiver 69 of the operator as an indication to her that the line is in use. Upon finding it in this condition, she will advise the calling party automatically, or by other well known means, that the called subscriber is unavailable. The calling party will then restore his receiver 16 and bring about a release in the manner hereinafter explained. In case the line is found idle, the operator will insert the plug P into the jack 122 of the line L', it being assumed that that is the line desired. Assuming that link-circuit N has direct access to line L' and that such line is similar to line L, then it will be seen that as soon as plug P is inserted into jack 122, a circuit will be completed through sleeve supervisory relay 73 which may be traced from the live pole of battery B, through the winding of relay 73, sleeve strand 66, sleeve contacts of the plug and jack, extension conductor 28 and the winding of cut-off relay 19 of the called line to ground. The closing of this circuit will energize relays 19 and 73. The former will thereupon extend

65 the circuit to the called substation, or sub-

stations, and cut off the line relay associated with that line. The latter will interrupt the circuit of control relay 70 at back contact 87 and thereby deenergize it so that in case there be another awaiting call, it will be immediately established, or if there be no such awaiting call, the apparatus and circuits will be available and ready to receive it when it comes. The energization of relay 73 will also interrupt the circuit of pilot relay 82 and call lamp 90. As a result both lamps 84 and 90 will be extinguished. The energization of this relay 73 will also interrupt the connection between the operator's receiver 69 and the strands of this particular link-circuit, such disconnection occurring at back contacts 96 and 97. By the actuation of its contact 108, relay 73 will also open the circuit of test relay 107 and connect tip supervisory relay 74 to tip strand 65. At the instant of inserting plug P into jack 122, the operator will depress one or other of the ringing keys to apply proper ringing current to ring the bell of the wanted party. But of course, if there are no party lines, the operator would depress but the usual ringing key. As a result, the call-bell at the desired substation will be rung and, upon the response of the called party, a circuit will be completed for tip supervisory relay 74. The ringing circuit, resulting from the depression of ringing key 115-116, would extend from the live pole of the ringing generator 117, through alternate contact 115, strand 65, plug and jack tip contacts, the tip side of the circuit of the called line, through the bell at the substation and back over the sleeve side of the line, to ground through its cut-off relay, or, alternatively, through the plug and jack sleeve contacts, strand 66, alternate contact 116, coil 118 and battery B to ground. At this time by reason of the connection of battery B through the coil 118 to the sleeve side of the circuit, the cut-off relay associated with line L' is maintained energized. In case ringing key 119-120 is depressed, the live pole of ringing generator 121 is connected to the sleeve side of the circuit and ground is connected to the tip side. Otherwise the ringing circuit is the same as above described. In the latter case, however, the current from the generator 121 is relied upon to maintain the cut-off relay of the line L' energized during the ringing operation. Upon the response of the called party, a bridge is completed at his substation for the flow of battery current through his induction coil 11 and transmitter 10 from the sleeve side to the tip side of the circuit and thence through the tip contacts of the jack and plug, strand 65, front contact 108 of relay 73, and the winding of tip supervisory relay 74 to ground. The closing of this latter circuit opens contact 80 of

70 75 80 85 90 95 100 105 110 115 120 125 130

this latter relay. Conversation may now be carried on between the calling and the called parties over the heavily marked conductors. It will be observed that as soon as 5 sleeve supervisory relay 73 is energized, the operator's set is freed for use with other link-circuits of the group and at the same time the guarding connection upon all the link-circuits of the group, resulting from 10 the energization of relay 70, is removed. Thus it is possible to obtain connection with a link-circuit of a particular group only when the operator's set is free and therefore 15 only when the operator is ready to receive an order from the calling party.

At the conclusion of conversation, the parties restore their receivers to their switch-hooks and, as a result, the tip supervisory relays 72 and 74 are deenergized. 20 The deenergization of relay 72 lights supervisory lamp 75, associated with the switch end of the link-circuit, by closing a circuit which may be traced from the live pole of the battery B, through the winding of relay 25 81, lamp 75, front contact 77 of relay 71 and back contact 78 of relay 72 to ground. The closing of this circuit also energizes relay 81 to close a circuit through pilot supervisory lamp 83 and front contact 85 of relay 30 81 to ground. On the other hand, the deenergization of relay 74 lights supervisory lamp 76 by closing a circuit which may be traced from the live pole of battery B, through lamp 76, front contact 79 of relay 35 73, and back contact 80 of relay 74 to ground. Upon observing the supervisory lamps lighted, the operator will take down the connection by removing plug P from jack 122. This will at once deenergize sleeve 40 supervisory relay 73 and extinguish lamp 76. It will also close a release circuit for the associated switch M. This circuit, as before traced, extends from the battery, through the winding of relay 82, front contact 45 93 of relay 71, back contact 92 of relay 73, back contact 91 of relay 72, conductor 67, switch contact 42, wiper 39, back contact 36 of relay 18 and the winding of release magnet 53 to ground. The closing of this 50 circuit will actuate said release magnet to cause the spring catch 50 on its armature 52 to engage the hooked projection 51 on retaining pawl 48 in readiness to withdraw said pawl upon deenergization of the release magnet to allow the switch to return to normal under the tension of its return spring 55. The engagement of catch 50 and projection 51 closes a circuit for magnet 20 from battery through the winding of said magnet, 60 catch 50, projection 51 and pawl 48 to ground. As a result of the closing of this circuit, relay 20 opens the circuit of the extending line at contacts 31 and 32. The opening of the latter contact breaks the previous circuit over the sleeve side through 65

sleeve supervisory relay 71 and cut-off relay 19. The return of the former extinguishes supervisory lamp 75 and pilot lamp 63. The return of the latter restores the line circuit to its normal condition. The return of the 70 sleeve supervisory relay 71 also breaks the release circuit through release magnet 53 and thereby allows spring 54 and catch 50 to withdraw the retaining pawl 48 and thus allow the switch parts to return to normal. 75 Thus all the parts are brought to normal in readiness for the initiation of another call.

In order that the switch M may be kept in operation until a link-circuit N, having contacts 59 and 60 are arranged so as to release the switch when it overruns its operative contacts, in case it does not make connection with an idle operator's set upon its first traverse, and thereby free it for a second, a third, or as many as may be necessary before a connection is established. As before explained, when the switch has stepped one step beyond the last operative contacts, projection 61 engages contact 59 and forces it 80 into engagement with contact 60. This closes a release circuit for magnet 53 which may be traced from the live pole of battery B, through protective resistance 61, contacts 60, 59, back contact 34 of relay 20, and winding of release magnet 53 to ground. When restored as a result of this release operation, the switch is in readiness to begin another traverse because the line relay 18 is still 85 energized. Similar traverses may follow. 90

It will, of course, be understood that the several ground connections in the diagram are connections to the return side of the battery. Likewise, where parts are common to a plurality of circuits, such as control relays 70, pilot relays 81 and 82, and the operators' sets, the common connections are indicated by a plurality of short lines radiating from the common connecting point. It will also be understood that when the 105 lines L', L², are trunk lines, then their circuits must be such as to bring about the operation of the tip and sleeve supervisory relays 73 and 74 and the associated connections, just as explained where the lines L' and L² were assumed to be subscribers' lines having line circuits similar to the line L. Many trunk circuits of the art are available for use with the particular form of link-circuit illustrated. One such instance will be found illustrated in Fig. 290 on page 368 of *American Telephone Practice*, by Kempster B. Miller, Fourth Edition, and described in the adjacent text. Other instances might be cited, but it is believed this one 110 115 will suffice.

As illustrative of relays having mechanical construction suitable for the operation of a plurality of contacts such as some of the relays in the present disclosure, attention is 120 125 130

directed to the following United States patents issued to E. E. Clement: 928,360, July 20, 1909; 990,032, April 18, 1911; 991,829, May 9, 1911. It will also be understood that the link-circuits accessible to any one group of switches M may be variously distributed before operators having control of the plugs P according to expediency or the will of the user. Likewise, the link-circuits of any one group may be divided among any desired number of operators and the various operators' sets may be made common to any desired individual link-circuits of the particular group.

15 It will also be apparent that other alterations and modifications may be made in the particular embodiment of the invention herein disclosed without departing from the spirit and scope of my invention and that 20 my invention is capable of extended application. I, therefore, do not wish to be limited to the particular embodiment herein disclosed, but aim to cover such alterations and modifications and the various applications thereof by the term of the appended claims.

What I claim as new and desire to secure by Letters Patent of the United States is:—

1. A telephone system comprising circuits severally available for calling purposes, an operator's telephone set common to said circuits, automatic switch mechanism for extending said circuits to said set, means under the control of an operator for further extending such extended circuits, and means for indicating to a party calling over one of said circuits when the operator's receiver is in circuit ready for the operator to receive such party's order.

2. A telephone system comprising a circuit available for calling purposes, an operator's telephone set for use with said circuit, other circuits for use with said set, automatic switch mechanism for extending said first mentioned circuit to said set, means under the control of an operator for further extending such extended circuit, and means for indicating to a party calling over said first mentioned circuit when the operator's receiver is in circuit ready for the operator to receive such party's order.

3. A telephone system comprising circuits severally available for calling purposes, operators' telephone sets available for connection to said circuits, means responsive to calls over said circuits to connect said sets to different calling circuits, means for indicating to such calling parties when the operators' sets are respectively in circuit ready for the operators to receive orders from such parties and means for freeing each said connecting means for further service after the receipt of the order over the connections established by it.

4. A telephone system comprising lines

severally available for calling purposes, link-circuits available for connection to said lines, an operator's telephone set common to said link-circuits, means responsive to the initiation of a call over any of said lines to connect the calling line to an idle one of said link-circuits, means for indicating to the calling party when the operator's receiver is in circuit ready for the operator to receive such party's order and means operative after the receipt of said order to free said connecting means for further service.

5. A telephone system comprising lines severally available for calling purposes, link-circuits available for connection to said lines, operators' sets available for connection to said link-circuits, means responsive to the initiations of calls over said lines to connect the calling lines to idle ones of said link-circuits, means for indicating to the calling parties when the operators' sets are in circuit ready for the operators to receive such parties' orders and means for freeing each said connecting means for further service after the receipt of the order over the connections established by it.

6. A telephone system comprising lines severally available for calling purposes, link-circuits available for connection to said lines, an operator's telephone set common to said link-circuits, means responsive to every initiation of a call over said lines to test said link-circuits successively in the same order and connect the calling line with an idle one of said link-circuits, means for indicating to the calling party when the operator's receiver is in circuit ready for the operator to receive such calling party's order, and means operative after the receipt of said order to free said connecting means for further service.

7. A telephone system comprising lines severally available for calling purposes, link-circuits available for connection to said lines, operators' set available for connection to said link-circuits, means responsive to all initiations of calls over said lines to test said link-circuits successively in the same order and connect the calling lines to idle ones of said link-circuits, means for indicating to the calling parties when the operators' sets are in circuit ready for the operators to receive such calling parties' orders, and means for freeing each said connecting means for further service after the receipt of the order over the connections established by it.

8. A telephone system comprising circuits severally available for calling purposes, a telephone receiver operatively associated with the calling end of each of said circuits, means responsive to the initiation of a call over any of said circuits to vary the electrical condition of said circuit to cause a characteristic sound in said receiver, an

operator's telephone set common to said circuits, means including automatic switch mechanism for connecting a calling circuit to said set, means for discontinuing the said sound in said receiver at the time said set is thus connected, and means subsequently operative to free said connecting means.

9. A telephone system comprising lines severally available for calling purposes, a telephone receiver operatively associated with the calling end of each of said circuits, means responsive to the initiation of a call over any of said circuits to vary the electrical condition of said circuit to cause a characteristic sound in said receiver, link-circuits available for connection to said lines, an operator's telephone set available for connection to said link-circuits, means including automatic switch mechanism for connecting a calling line to an idle one of said link-circuits, means for connecting said operator's set to the same idle link-circuit, means for discontinuing the said sound in said receiver at the time said set is thus connected, and means subsequently operative to free said connecting means.

10. A telephone system comprising subscribers' lines extending from substations to an exchange, subscribers' telephone sets operatively associated with said lines at the substations, a line relay included in circuit with each said line upon initiation of a call thereover, means operated by said relay to vary the electrical condition of the associated circuit to cause a characteristic sound in the calling party's receiver, link-circuits available for connection to said subscribers' lines, an operator's telephone set available for connection to said link-circuits, means for connecting a calling line to an idle one of said link-circuits, means for connecting said operator's set to the same idle link-circuit, and means for discontinuing the said sound in the calling party's receiver at the time said operator's set is thus connected.

11. A telephone system comprising subscribers' lines extending from substations to an exchange, subscribers' telephone sets operatively associated with said lines at the substations, a line relay included in circuit with each said line upon initiation of a call thereover, means operated by said relay to vary the electrical condition of the associated circuit to cause a characteristic sound in the calling party's receiver, link-circuits available for connection to said subscribers' lines, an operator's telephone set available for connection to said link-circuits, means for connecting a calling line to an idle one of said link-circuits, means for connecting said operator's set to the said idle link-circuit, a cut-off relay for opening the circuit of said line relay to discontinue the said sound in the calling party's receiver, and

means for operating said cut-off at the time said operator's set is thus connected.

12. A telephone system comprising circuits severally available for calling purposes, an operator's telephone set common to said circuits, means responsive to the initiation of a call over any of said circuits to extend such circuit into conversational connection with the operator's set but only when said set is free for use, and means under the control of an operator for further extending such an extended circuit.

13. A telephone system comprising a circuit available for calling purposes, an operator's telephone set for use with said circuit, other circuits for use with said set, means responsive to the initiation of a call over said first-mentioned circuit to extend it into conversational connection with said operator's set but only when said set is free for use, and means under the control of an operator for further extending such extended circuit.

14. A telephone system comprising circuits severally available for calling purposes, operators' telephone sets available for connection to said circuits, means responsive to calls over said circuits to extend said circuits individually into conversational connection with said sets but only when said set is free for use, and means under the control of an operator for further extending such extended circuits.

15. A telephone system comprising lines severally available for calling purposes, link-circuits available for connection to said lines, an operator's telephone set common to said link-circuits, means responsive to the initiation of a call over any of said lines to connect the calling line into conversational connection with one of said link-circuits and thence to said operator's set but only when the latter is free for use and means under operator control for further extending the conversational circuit thus established.

16. A telephone system comprising lines severally available for calling purposes, link-circuits available for connection to said lines, operators' sets available for connection to said link-circuits, means responsive to the initiations of calls over said lines to certain of said link-circuits and thence into conversational connection with said operators' sets but only when the latter are free for use and means under operator control for further extending the conversational circuits thus established.

17. A telephone system comprising lines severally available for calling purposes, link-circuits available for connection to said lines, operators' sets available for connection to said link-circuits, means responsive to the initiation of a call over any of said lines to connect the calling line to one of said link-

circuits and thence into conversational connection with one of said operators' sets but only when the latter is free for use and means under operator control for further 5 extending the conversational circuit thus established.

18. A telephone system comprising lines severally available for calling purposes, link-circuits available for connection to said lines, 10 an operator's telephone set common to said link-circuits, means responsive to the initiation of a call over any of said lines to connect the calling line and an idle one of said link-circuits into a conversational circuit 15 with the operator's set and means under operator control for further extending the conversational circuit thus established.

19. A telephone system comprising lines severally available for calling purposes, link- 20 circuits available for connection to said lines, operators' sets available for connection to said link-circuits, means responsive to the initiations of calls over said lines to connect the calling lines and idle ones of said link- 25 circuits into conversational circuits with the associated operators' sets and means under operator control for further extending the conversational circuits thus established.

20. A telephone system comprising lines 30 severally available for calling purposes, link-circuits available for connection to said lines, operators' sets available for connection to said link-circuits, means responsive to the initiation of a call over any of said lines to 35 connect the calling line and an idle one of said link-circuits into a conversational circuit with the operator's set associated with that link-circuit and means under operator control for further extending the conversational 40 circuit thus established.

21. A telephone system comprising lines severally available for calling purposes, link-circuits available for connection to said lines, 45 an operator's telephone set common to said link-circuits, means responsive to every initiation of a call over said lines to test said link-circuits successively in the same order and connect the calling line and an idle one of said link-circuits into a conversational 50 circuit with said operator's set and means under operator control for further extending the conversational circuit thus established.

22. A telephone system comprising lines 55 severally available for calling purposes, link-circuits available for connection to said lines, operators' sets available for connection to said link-circuits, means responsive to all initiations of calls over said lines to 60 test said link-circuits successively in the same order and connect the calling lines and idle ones of said link-circuits into conversational circuits with the associated operators' sets and means under operator control for

further extending the conversational circuit thus established. 65

23. A telephone system comprising lines severally available for calling purposes, link-circuits available for connection to said lines, operators' sets available for connection to said link-circuits, means responsive to every initiation of a call over said lines to test said link-circuits successively in the same order and connect the calling line and an idle one of said link-circuits into a conversational circuit with the operator's set associated with that link-circuit and means under operator control for further extending the conversational circuit thus established. 70

24. A telephone system comprising circuits severally available for calling purposes, an operator's telephone set common to said circuits, means responsive to the initiation of a call over any of said circuits to extend such circuit into conversational connection with the operator's set but only when said set is free for use, means operative upon the establishment of such extension to indicate to the calling party that the operator is free and ready to receive such calling party's order, and means under the control of an operator for further extending such an extended circuit. 75

25. A telephone system comprising a circuit available for calling purposes, an operator's telephone set for use with said circuit, other circuits for use with said set, means responsive to the initiation of a call over said first mentioned circuit to extend it into conversational connection with said operator's set but only when said set is free for use, means operative upon the establishment of such extension to indicate to the calling party that the operator is free and ready to receive such calling party's order, and means under the control of an operator for further extending such extended circuit. 80 85 90 95

26. A telephone system comprising circuits severally available for calling purposes, operators' telephone sets available for connection to said circuits, means responsive to calls over said circuits to connect said circuits individually to said sets when free for use, means operative upon the establishment of such connections to indicate to the calling parties that their respective operators are ready to receive such calling parties' orders, and means for freeing each said connecting means for further service after the receipt of the order over the connections established by it. 100 105 110 115

27. A telephone system comprising lines severally available for calling purposes, link-circuits available for connection to said circuits, an operator's telephone set common to said link-circuits, a relay common to said 120 125

- link-circuits, automatic means for connecting a calling line to an idle one of said link-circuits whenever said relay is deenergized, means for deenergizing said relay only when said operator's set is free for use, and means for automatically connecting said operator's set into conversational connection with the utilized link circuit.
28. A telephone system comprising lines severally available for calling purposes, link-circuits available for connection to said lines, other lines severally available as called lines; an operator's telephone set common to said link-circuits, means under the operator's control for connecting said link-circuits to said other lines, a relay common to said link-circuits, automatic means operative in response to a call over any of said first mentioned lines to connect such line to an idle link-circuit whenever said relay is deenergized, means responsive to the connection of a selected link-circuit to a called line to deenergize said relay, and means for automatically connecting said operator's set into conversational connection with the utilized link circuit.
29. A telephone system comprising circuits severally available for calling purposes, operators' telephone sets available for connection to said circuits, means responsive to the initiation of a call over any of said circuits to test said operators' sets successively and connect said calling circuit into conversational connection with the first said set found idle and means under operator control for further extending the conversational circuit thus established.
30. A telephone system comprising a circuit available for calling purposes, operators' sets available for use with said circuit and otherwise, means responsive to the initiation of a call over said circuit to test said operators' sets successively and connect said calling circuit into conversational connection with the first said set found idle and means under operator control for further extending the conversational circuit thus established.
31. A telephone system comprising circuits severally available for calling purposes, operators' telephone sets available for connection to said circuits, means responsive to the initiations of calls over said circuits to test said operators' sets successively and connect said calling circuits individually into conversational connection with the first said set found idle and means under operator control for further extending the conversational circuit thus established.
32. A telephone system comprising lines severally available for calling purposes, link-circuits available for connection to said lines, operators' sets available for connection each to a plurality of said link-circuits, means responsive to the initiation of a call over any of said lines to test the link-circuits of the different operators' sets successively and connect such calling line through a link-circuit into conversational circuit with the first operator's set found idle and means under operator control for further extending the conversational circuit thus established.
33. A telephone system comprising lines severally available for calling purposes, link-circuits available for connection to said lines, operators' sets available for connection each to a plurality of said link-circuits, means responsive to the initiations of calls over said lines to test the link-circuits of the different operators' sets successively and connect such calling lines respectively through link-circuits into conversational circuits with the first operators' sets found idle and means under operator control for further extending the conversational circuits thus established.
34. A telephone system comprising lines severally available for calling purposes, link-circuits available for connection to said lines, operators' sets available for connection each to a plurality of said link-circuits, means responsive to every initiation of a call over said lines to test the link-circuits of the different operators' sets successively in the same order and connect the calling line through a link-circuit into conversational circuit with the first operator's set found idle and means under operator control for further extending the conversational circuit thus established.
35. A telephone system comprising lines severally available for calling purposes, link-circuits available for connection to said lines, operators' sets available for connection each to a plurality of said link-circuits, means responsive to all initiations of calls over said lines to test the link-circuits of the different operators' sets successively in the same order and connect the calling lines respectively through link-circuits into conversational circuits with the first operators' sets found idle and means under operator control for further extending the conversational circuits thus established.
36. A telephone system comprising circuits severally available for calling purposes, operators' telephone sets available for connection to said circuits, means responsive to the initiation of a call over any of said circuits to test said operators' sets successively and connect said calling circuit to the first said set found idle, means for indicating to the calling party when the operator's receiver is in circuit ready for the operator to receive such calling party's order and means operative after the receipt of said order to free said connecting means for further service.
37. A telephone system comprising circuits severally available for calling purposes, operators' telephone sets available for connection each to a plurality of said link-circuits, means responsive to the initiations of calls over said lines to test the link-circuits of the different operators' sets successively and connect such calling lines respectively through link-circuits into conversational circuits with the first operators' sets found idle and means under operator control for further extending the conversational circuits thus established.

nection to said circuits, means responsive to the initiation of a call over any of said lines to automatically bring one of said operators' sets into connection with said calling circuit, 5 means for indicating to the calling party when the receiver of operator, whose set is thus connected, is connected in circuit and ready for the operator to receive such calling party's order and means operative after 10 the receipt of said order to free said connecting means for further service.

38. A telephone system comprising circuits severally available for calling purposes, operators' telephone sets available for 15 connection to said circuits, a relay individual to each operator's set, means for maintaining said relays energized or deenergized according to the busy or idle conditions of the associated operators' sets respectively, means 20 responsive to the initiation of a call over any of said circuits to test the conditions of said relays and to connect said calling line into conversational circuit with the operator's set whose relay is first found idle 25 and means under operator control for further extending the conversational circuit thus established.

39. A telephone system comprising lines severally available for calling purposes, 30 link-circuits available for connection to said lines, operators' telephone sets available for connection to said link-circuits, a relay for each operator's set, means for maintaining said relays energized or deenergized according 35 to the busy or idle condition of the associated operators' sets respectively, means responsive to the initiation of a call over any of said circuits to test the conditions of said relays and to connect said calling line 40 to a link-circuit and thence into conversational circuit with that operator's set whose relay is first found idle and means under operator control for further extending the conversational circuit thus established.

40. A telephone system comprising lines severally available for calling purposes, link-circuits available for connection to said lines, switch mechanism for connecting said lines and link-circuits, said mechanism including test contacts, telephone sets available for connection to said link-circuits, relays individual to said operators' sets and operative to determine the busy or idle condition of said test contacts according to the 50 busy or idle condition of the respective operators' sets, means responsive to the initiation of a call over any of said lines to operate said switch mechanism to connect the calling line to a link-circuit and thence into conversational circuit with the operator's set whose relay is first found idle and means under operator control for further extending the conversational circuit thus established.

41. A telephone system comprising lines

severally available for calling purposes, link-circuits available for connection to said lines, other lines severally available as called lines, operators' telephone sets available for connection to said link-circuits, relays individual to said operators' sets, means under the control of the operators for connecting said link-circuits to said other lines, means for connecting calling lines to idle link-circuits and thence into conversational circuits with said operators' sets according to the energized or deenergized conditions of said relays, means for energizing said relays in response to the connections of calling lines to link-circuits associated with them, means 70 for deenergizing said relays in response to the connections of selected associated link-circuits to said other lines as called lines and means under operator control for further extending the conversational circuits 75 thus established.

42. A telephone system comprising circuits severally available for calling purposes, an operator's telephone set common to said circuits, automatic switch mechanism for 90 extending said circuits into conversational connection with said set, means under the control of an operator for further extending such extended circuits, and means for preventing said mechanism from extending 95 a calling circuit until the orders of all previous calls have been received by an operator.

43. A telephone system comprising circuits severally available for calling purposes, operators' telephone sets available for connection to said circuits, automatic switch mechanism for extending said circuits into conversational connection with said sets, means under operator control for further extending such extended circuits, and means 100 for preventing said mechanism from extending a calling circuit to any particular operator's set until the orders of all previous calls for that operator have been received by her.

44. A telephone system comprising circuits severally available for calling purposes, an operator's telephone set common to said circuits, automatic switch mechanism responsive to calls over said circuits to extend 115 said circuits into conversational connection with said set, said mechanism refusing to thus extend more than one circuit so long as said set is in use, and means under operator control for further extending such 120 extended circuits.

45. A telephone system comprising circuits severally available for calling purposes, operators' telephone sets available for connection to said circuits, automatic switch mechanism responsive to calls over said circuits to extend said circuits into conversational connection with said sets, said mechanism refusing to extend more than one circuit per set so long as said set is in use,

and means under operator control for further extending such extended circuits.

46. A telephone system comprising lines severally available for calling purposes, 5 link-circuits available for connection to said lines, an operator's telephone set common to said link-circuits, means responsive to calls over said lines to connect said set to said link-circuits and thence to the calling 10 lines, the set being connected to but one link-circuit and line at a time and means under operator control for further extending the circuit thus established by said connecting means.
47. A telephone system comprising lines severally available for calling purposes, link-circuits available for connection to said lines, operators' telephone sets available for connection to said link-circuits, means responsive to calls over said lines to connect said sets to different link-circuits and thence to different calling lines, each set being connected to but one link-circuit and line at a time and means under operator control for 25 further extending the circuit thus established by said connecting means.

48. A telephone system comprising circuits severally available for calling purposes, an operator's telephone set common 30 to said circuits, means for automatically restricting the operator's attention to one call at a time, means for indicating to the calling party when the operator's receiver is in circuit ready for the operator to receive 35 such calling party's order and means operative after the receipt of said order to free said restricting means for further service.

49. A telephone system comprising circuits severally available for calling purposes, operators' sets available for connection to said circuits, means responsive to the initiations of calls over said circuits to automatically bring said operators' sets into several connection with said calling circuits, means for indicating to the calling parties when the operators' sets are in circuit ready for the operators to receive the calling parties' orders and means for freeing each said connecting means for further service 50 vice after the receipt of the order over the connections established by it.

50. A telephone system comprising circuits severally available for calling purposes, an operator's telephone set common 55 to said circuits, means responsive to the initiation of a call over any of said circuits to connect such circuit into conversational circuit with said operator's set when idle, means for preventing other calling circuits 60 from being connected therewith until the operator has performed a subsequent act and means under operator control for further extending the conversational circuit thus established.

51. A telephone system comprising circuits severally available for calling purposes, an operator's telephone set common to said circuits, means responsive to the initiation of a call over any of said circuits to connect such circuit into conversational 70 circuit with said operator's set when idle, a relay for determining the selectivity of said operator's set, means under the control of the operator for actuating said relay and means under operator control for further 75 extending the conversational circuit thus established.

52. A telephone system comprising circuits severally available for calling purposes, an operator's set common to said circuits, a control relay, means responsive to the initiation of a call over any of said circuits to connect said circuit into conversational circuit with said operator's set upon one condition of said relay and to pass by 80 said set upon another condition of said relay, relays and circuits under the control of the calling party and the operator for establishing the different conditions of said relay and means under operator control for 85 further extending any conversational circuit thus established.

53. A telephone system comprising lines severally available for calling purposes, link-circuits available for connection to said 95 lines, an operator's set common to said link-circuits, switch mechanism for connecting said lines and link-circuits, relays and circuits for connecting said operator's set to said link-circuits, a control relay for determining the action of said switch mechanism and said relays and circuits, and means under the control of the operator for determining the action of said control relay.

54. A telephone system comprising lines 10 severally available for calling purposes, link-circuits available for connection to said lines, other lines available as called lines, an operator's set available for connection to said link-circuits, switch mechanism for connecting said lines and link-circuits, relays and circuits for connecting said operator's set to said link-circuits, a control relay for determining the action of said switch mechanism and said relays and circuits according 11 to its energized or deenergized condition, means responsive to the connection of said lines and link-circuits to energize said control relay, and means responsive to the connection of said link-circuits to said other 12 lines to deenergize said control relay.

55. A telephone system comprising circuits severally available for calling purposes, an operator's telephone set available for connection to said circuits, automatic 12 means dependent upon the idle condition of said operator's telephone set for extending a calling one of said circuits into conver-

sational connection with said set, and means under operator control for further extending such an extended circuit.

56. A telephone system comprising a circuit available for calling purposes, an operator's telephone set available for use with said circuit, other circuits for use with said set, automatic means dependent upon the idle condition of said operator's telephone set for extending said first-mentioned circuit into conversational connection with said set, and means under operator control for further extending such extended circuit.

57. A telephone system comprising circuits severally available for calling purposes, operators' telephone sets available for connection to said circuits, automatic means dependent upon the idle condition of said operators' sets to extend calling ones of said circuits into conversational connection with said sets severally, and means under operator control for further extending such extended circuits.

58. A telephone system comprising lines severally available for calling purposes, link-circuits available for connection to said lines, an operator's telephone set available for connection to said link-circuits, and means dependent upon the idle condition of said operator's set for connecting it to one of said link-circuits and thence automatically to a calling one of said lines.

59. A telephone system comprising a line available for calling purposes, link-circuits available for connection to said line, an operator's telephone set available for use with said link-circuits and otherwise, and means dependent upon the idle condition of said operator's telephone set for connecting it to one of said link-circuits and thence automatically to said line in response to a call over said line.

60. In a telephone system comprising lines severally available for calling purposes, link-circuits available for connection to said lines, operators' telephone sets available for connection to said link-circuits, and means dependent upon the idle condition of said operators' sets to connect said sets to different link-circuits and thence automatically to different calling lines.

61. A telephone system comprising circuits severally available for calling purposes, an operator's telephone set available for connection to said circuits, means dependent upon the idle condition of said operator's set for connecting it to a calling one of said circuits, means for indicating to the calling party when the operator's receiver is in circuit ready for the operator to receive his order and means under operator control for further extending the conversational circuits thus established.

62. A telephone system comprising cir-

cuits severally available for calling purposes, operators' telephone sets available for connection to said circuits, means dependent upon the idle condition of said operators' telephone sets to connect them severally to calling ones of said circuits, means for severally indicating to the calling parties when the operators' sets are in circuit ready for the operators to receive their orders and means for freeing each said connecting means for further service after the receipt of the order over the connections established by it.

63. A telephone system comprising circuits severally available for calling purposes, an operator's telephone set available for connection to said circuits, a control relay, means for giving it a definite electrical condition when said operator's set is not in use, means for automatically connecting a calling one of said circuits into conversational connection with said operator's set while said control relay is in said electrical condition and means under operator control for further extending the conversational circuits thus established.

64. A telephone system comprising circuits severally available for calling purposes, an operator's set available for connection to said circuits, a control relay being energized or deenergized according to the busy or idle condition of said operator's set, traveling means responsive to the initiation of a call over any of said circuits to pass or establish a conversational circuit with said operator's set according to the energized or deenergized condition of said control relay and means under operator control for further extending the conversational circuits thus established.

65. A telephone system comprising lines severally available for calling purposes, link-circuits available for connection to said lines, an operator's telephone set available for connection to said link-circuits, a control relay having definite electrical conditions corresponding to the busy and idle conditions of said operator's set, automatic switch mechanism for connecting said lines and link-circuits into conversational circuits with said operator's set, means for determining the operation of said mechanism according to the condition of said control relay and means under operator control for further extending the conversational circuits thus established.

66. A telephone system comprising lines severally available for calling purposes, link-circuits available for connection to said lines, an operator's telephone set available for connection to said link-circuits, automatic switch mechanism for connecting said lines and link-circuits into conversational circuits with said operator's set, other lines

available for connection as called lines, means under the operator's control for bringing about such latter connections and extending the conversational circuits thus established to include said called lines, a control relay, means for closing a circuit for said relay upon the connection of a calling line to a link-circuit, means for opening said circuit upon the connection of a link-circuit to one of said other lines, and circuits controlled by said control relay for determining the selectability of said link-circuits individually.

67. A telephone system comprising circuits severally available for calling purposes, other circuits severally available for called purposes, means, including automatic switch mechanism, for uniting calling and called circuits, part of said means being under the control of an operator, an operator's telephone set adapted for inclusion in a conversational circuit with a party calling over one of said calling circuits, and means for indicating to such a calling party when the operator's receiver is in circuit ready for the operator to receive such party's order.

68. A system comprising circuits severally available for calling purposes, calling mechanism associated with each of said circuits requiring a plurality of acts on the part of the calling party to make a call, receiving mechanism common to said circuits, automatic switch mechanism for extending said circuits to said receiving mechanism, means under operator control for further extending such extended circuits, and means responsive to the initiation of a call over any of said circuits to indicate when said receiving mechanism is in condition for the subsequent act, or acts, of the calling party.

69. A telephone system comprising circuits severally available for calling purposes, other circuits severally available for called purposes, an operator's telephone set common to said first mentioned circuits, automatic switch mechanism responsive to the initiation of a call over any of said circuits to extend such circuit into conversational connection with the operator's set, but only when said set is free for use, and means under the control of an operator for combining with said switch mechanism to unite calling and called circuits.

70. A telephone system comprising circuits severally available for calling purposes, other circuits severally available for called purposes, an operator's telephone set common to said first mentioned circuits, automatic switch mechanism responsive to the initiation of a call over any of said circuits to extend such circuit into conversational connection with the operator's set, but only when said set is free for use, means operative upon the establishment of such exten-

sion to indicate to the calling party that the operator is free to receive the calling party's order, and means under the control of an operator for combining with said switch mechanism to unite calling and called circuits.

71. A system comprising circuits severally available for calling purposes, calling mechanism associated with the calling end of each said circuit, requiring a plurality of acts on the part of the calling party to make a call, receiving mechanism common to said circuits, means responsive to the initiation of a call over any of said circuits to connect such calling circuit with said receiving mechanism when the latter is free for use, means for indicating to the calling party that said receiving mechanism is in condition for such party's further calling act, or acts and means operative after the performance of said act, or acts, to free said connecting means for further service.

72. A telephone system comprising circuits severally available for calling purposes, other circuits severally available for called purposes, means, including automatic switch mechanism, for uniting calling and called circuits, part of said means being under the control of an operator, means co-operating with said uniting means to enable orders of calling parties to be communicated to an operator, and means for preventing the communication of any such calling party's order until all the orders of previously calling parties have been received by the operator and the operator's receiver is in circuit ready for the operator to receive such order.

73. A telephone system comprising circuits severally available for calling purposes, other circuits severally available for called purposes, means, including automatic switch mechanism, for uniting calling and called circuits, part of said means being under the control of an operator, and means co-operating with said uniting means in response to calls over said circuits to enable orders of calling parties to be communicated to an operator and to prevent the communication of any such calling party's order so long as the orders of previously calling parties have not been received by the operator and the operator's receiver is in circuit ready for the operator to receive such order.

74. A system comprising circuits severally available for calling purposes, calling mechanism associated with the calling end of each said circuit, requiring a plurality of acts on the part of the calling party to make a call, receiving mechanisms available for connection to said circuits, means responsive to the initiation of a call over any of said circuits to test said receiving mechanisms suc-

sively and connect such calling line to the first such receiving mechanism found idle, means for indicating to the calling party that the said receiving mechanism thus connected is in condition for such party's further calling act, or acts and means operative after the performance of said act, or acts, in the case of any particular call to free the corresponding connecting means for further

10 service.

75. A telephone system comprising circuits severally available for calling purposes, other circuits severally available for called purposes, means, including automatic 15 switch mechanism, for uniting calling and called circuits, part of said means being under the control of an operator, an operator's telephone set, and means coöperating with said uniting means to extend a calling 20 one of said circuits into conversational connection with said set, said combined means being dependent in their extending function upon the idle condition of said operator's telephone set.

76. A system comprising circuits severally available for calling purposes, calling mechanism associated with the calling end of each said circuit, requiring a plurality of acts on the part of the calling party to make 25 a call, a receiving mechanism common to said circuits, means for automatically connecting, and restricting the connection of, said receiving mechanism to one of said circuits at a time, means for indicating to 30 the calling party when said receiving mechanism is in condition for such party's further calling act, or acts, and means operative after the performance of said act, or acts, to free said connecting means for 35 further service.

77. A system comprising lines severally available for calling purposes, conductors available for interchangeable connection to said lines, receiving mechanism available 45 for connection to said conductors, and means dependent upon the idle condition of said receiving mechanism for connecting it to one of said conductors and thence automatically to a calling one of said lines.

78. A system comprising circuits severally available for calling purposes, calling mechanism associated with the calling end of each said circuit, requiring a plurality of acts on the part of the calling party to make 50 a call, a receiving mechanism available for connection to said circuits, means dependent upon the idle condition of said receiving mechanism for connecting said mechanism to a calling one of said circuits, means for 55 indicating to the calling party when said

receiving mechanism is in condition for such party's further calling act, or acts and means operative after the performance of said act, or acts, to free said connecting means for further service.

65

79. A system comprising circuits severally available for calling purposes, a receiver operatively associated with the calling end of each of said circuits, means responsive to the initiation of a call over any 70 of said circuits to continuously operate said receiver, a receiving telephone common to said circuits, means for connecting a calling circuit to said receiving telephone, means for discontinuing the operation of said receiver as soon as and only as soon as said receiving telephone is thus connected and means subsequently operative to free said connecting means.

75

80. A system comprising lines severally available for calling purposes, a receiver associated with the calling end of each of said circuits, a line relay included in circuit with each said line upon initiation of a call thereover, means operated directly by said relay 85 to continuously operate said receiver, conductors available for interchangeable connection to said lines, a receiving telephone available for connection to said conductors, means for connecting a calling line to an 90 idle conductor, means for connecting said receiving telephone to the same conductor, and means for discontinuing the operation of said receiver as soon as said receiving mechanism is thus connected.

95

81. A system comprising lines severally available for calling purposes, a receiver associated with the calling end of each of said circuits, a line relay included in circuit with each said line upon initiation of a call thereover, means operated by said relay to continuously operate said receiver, conductors available for connection to said lines, receiving mechanism available for connection to said conductors, means for connecting a calling line to an idle conductor, means for connecting said receiving mechanism to the same conductor, a cut-off relay for opening the circuit of said line relay to discontinue the operation of said receiver by reason of the means controlled 105 by said latter relay, and means for operating said cut-off relay as soon as said receiving mechanism is thus connected.

110

In witness whereof, I hereunto subscribe my name this 5th day of November, 1912.

115

LE ROY W. STANTON.

Witnesses:

T. H. FERGUSON,
J. W. BENNETT.

Corrections in Letters Patent No. 1,156,253,

It is hereby certified that in Letters Patent No. 1,156,253, granted October 12, 1915, upon the application of Le Roy W. Stanton, of Cleveland, Ohio, for an improvement in "Telephone Systems," errors appear in the printed specification requiring correction as follows: Page 1, line 93, for the word "substantion" read *substation*; page 4, line 20, before the word "is" insert the word *it*; page 7, line 110, claim 7, for the word "set" read *sets*; page 8, line 50, claim 11, before the word "line" insert the article *a*; page 13, line 63, claim 61; lines 89-90, claim 63, and line 103, claim 64, for the word "circuits" read *circuit*; and that the said Letters Patent should be read with these corrections therein that the same may conform to the record of the case in the Patent Office.

Signed and sealed this 2nd day of November, A. D., 1915.

[SEAL.]

R. F. WHITEHEAD,

Acting Commissioner of Patents.
